UNITED STATES PATENT OFFICE.

JOHN A. CHANDLER, OF KANSAS CITY, MISSOURI, ASSIGNOR TO THE STANDARD FILTER COMPANY, OF SAME PLACE.

FILTER.

SPECIFICATION forming part of Letters Patent No. 609,754, dated August 23, 1898.

Application filed October 26, 1897. Serial No. 656,381. (No model.)

To all whom it may concern:

Be it known that I, JOHN A. CHANDLER, of Kansas City, Jackson county, Missouri, have invented certain new and useful Improvements in Filters, of which the following is a full, clear, and exact description, reference being had to the accompanying drawings, forming a part thereof.

My invention relates to filters, and more particularly to filters of that class which are coupled onto pipes or faucets from which water is discharged under pressure; and it consists in certain novel and peculiar features of construction and combinations of parts hereinafter described and claimed.

The object of the invention is to produce a filter of this character which filters the water thoroughly and is of simple, strong, durable, and knockdown construction, to the end that the filtration-cylinder may be easily and quickly removed, cleaned, and replaced in its casement.

Other objects of the invention will herein-after appear, and be pointed out in appended claims.

In the accompanying drawings, Figure 1 represents a central vertical section of a filter embodying my invention. Fig. 2 represents a top plan view of the same. Fig. 3 is a horizontal section taken on the line III III of Fig.

1. Fig. 4 is a horizontal section taken on the line IV IV of Fig. 1.

In the said drawings, 1 designates a vertical cylinder provided at its lower end with a screw-threaded passage or opening 2, mounted upon the upper end of an elbow 3, coupled in the customary manner to the discharge-pipe (not shown) of a waterworks system, said pipe being provided with a valve 4 for controlling the passage of the water therethrough. The cylinder or casement is diametrically enlarged at its upper end, as shown at 5, and is provided externally with an annular horizontal flange 6.

7 designates a packing-ring, of rubber or its equivalent, which depends into the enlargement 5 of the cylinder or casement and is provided at its upper end with an outwardly-projecting horizontal flange 8, which rests upon the flange 6 of the casement, but is provided

in its outer edge at suitable intervals with notches for a purpose which will presently appear.

10 designates a clamp-ring which is of angular form in cross-section and is clamped down upon the flange 8 of the packing-ring by means of a series of screw-bolts 11, which extend up through the flange 6 of the casement, the notches 9 of the packing-ring, and into threaded holes in said clamp-ring, as shown clearly in Fig. 1.

12 designates a clamp-plate provided with an upwardly-projecting annular wall 13 about equal in depth to the packing-ring and flaring upwardly and outwardly slightly by preference. Said plate is provided centrally at its upper side with an internally-threaded boss 14 and at its under side with a boss 15, which tapers at its lower end. The boss 15 is provided with radial passages 16 just below the plate and with a vertical passage 17, which forms a channel for communication between the passages 16 and the hollow discharge-pipe 18, screwed down into the boss 14, and of approximately semicircular form at its upper end. The boss 15 is furthermore provided centrally with a recess in which fits snugly the upper end of a tie-rod 19, said rod being secured in such position by means of a cross-pin 20, as shown.

21 designates a washer, of rubber or equivalent material, which is fitted at the bottom of the clamp-plate concentrically of its center. Said packing-ring is of smaller diameter, preferably, than said clamp-plate, and is provided with a central opening 22, having a diameter somewhat larger than the boss 15, which it encircles.

23 designates the filtration stone or substance. It is of tubular form and is fitted endwise against the washer 21 and is of smaller diameter than the casement in order that an annular space or passage may be provided between the two. A packing-disk 24, of rubber or equivalent material, fits squarely against the bottom of said filtration-cylinder and snugly upon the tie-rod depending axially through it. A thin metallic plate 25 upon said rod bears against the under or opposite side of said packing-disk and is clamped

95 100

tightly against the same by means of a nut 26 upon the threaded end of said rod in order that by grasping and raising the gooseneck the filtration-cylinder may be lifted bodily 5 out of the casement 1 and quickly cleansed by brushing or scrubbing the dirt from its outer surface in the customary manner.

By reference to Fig. 1 it will be noted that the tendency of the water impinging forcibly 10 against the plate and packing-disk at the base of the cylinder would tend to lift the latter upwardly out of the casement. To prevent such action taking place I employ a latch-bar 27, which is provided centrally with a hole 28, 15 fitting loosely upon the tube or pipe 18 and of length to rest upon the horizontal portion of the angle clamp-ring 10, in order that under pivotal manipulation its ends may be caused to pass under the oppositely-disposed 20 hooks 29, cast integral with said clamp-ring.

When the parts of the filter are assembled as shown and the water turned on, it is obvious that the latter as it passes up through the annular space surrounding the filtration- 25 cylinder enters the enlargement of the casting externally of the packing-ring and there exerting an inward pressure forces the packing-ring 7 against the external surface of the flange 13 of the clamp-plate 12 so tightly that 30 it is absolutely impossible for the water to pass up between said parts. It is obvious also that the water exerting such pressure cannot escape between the flange of the packing-ring and the upper end of the flange 6 of 35 the casement, because the flange of said packing-ring is clamped down upon the flange 6 by means of the clamp-ring 10. As the water is thus confined it obviously must seep through the tubular filtration-cylinder for its 40 full length and pass up through the channel of the same and around the boss 15, (whose ends taper to afford as little obstruction as possible,) through the grooves 30, formed in the upper end of the cylinder to receive the 45 projecting ends of the pin 20, and into the opening 22 of the washer 21, from which chamber it passes freely, by way of the connecting passages 16 and 17, through the communicating discharge tube or pipe 18.

50 When it is desired to remove the filtration-cylinder to cleanse it, the latch-bar 27 is pivotally operated to disengage it from the hooks 29, and then by grasping the discharge-tube 18 the filtration-cylinder may be lifted bodily 55 out of the casement, as hereinbefore explained.

Such changes as do not involve a departure from the spirit and scope of the invention I reserve the right to make.

Having thus described the invention, what 60 I claim as new, and desire to secure by Letters Patent, is—

1. A filter comprising a casement having an opening in its bottom to receive the unfiltered water, a flexible packing-ring clamped in the 65 upper end of said casement, a clamp-plate embraced snugly by said packing-ring and provided with a discharge-tube, a tubular

filtration-cylinder in said casement, a washer or packing-ring provided with a central opening, clamped by said filtration-cylinder 70 against the bottom of said clamp-plate, said washer-opening affording communication between the channel of the filtration-cylinder and said discharge-pipe, and a packing-disk clamped up against the bottom of the filtration-cylinder, substantially as described. 75

2. A filter, comprising a casement having an opening in its bottom to receive the unfiltered water and enlarged diametrically at its upper end, a packing-ring depending into 80 the enlargement of the cylinder and provided with a flange resting upon the upper end of the cylinder, and a ring clamped down upon the flange of said packing-ring, in combination with a clamp-plate provided with a wall 85 externally and snugly embraced by said packing-ring, and provided also with a central passage and a discharge-pipe communicating therewith, a washer or packing-ring at the bottom of said plate and provided with a central opening in communication with the central passage of the plate, a tubular filtration-stone having its channel in communication with the opening of said washer or packing-ring, and clamping said washer or ring firmly 90 against the bottom of said plate, a packing-disk clamped against the lower end of said tubular filtration-stone, and a connection between said packing-disk and said clamp-plate, to the end that the removal of the latter will insure the removal of the former and the interposed stone, substantially as described. 95

3. A filter, comprising a casement having an opening in its bottom, to receive the unfiltered water, a flexible packing-ring clamped in the upper end of said casement, a clamp-plate embraced snugly by said packing-ring and provided with a discharge-tube, a tubular filtration-cylinder in said casement, a 100 washer or packing-ring provided with a central opening, clamped by said filtration-cylinder against the bottom of said clamp-plate, said washer-opening affording communication between the channel of the filtration-cylinder and said discharge-pipe, a packing-ring clamped up against the bottom of said filtration-cylinder, and means to lock the clamp-plate and the connected parts in their 105 operative positions within the casement, substantially as described. 110

4. A filter, comprising a casement having an opening in its bottom to receive the unfiltered water, a flexible packing-ring in and upon the upper end of the casement, a clamp-ring clamping said packing-ring down upon the casement, and provided at diametrically opposite points with oppositely-disposed hooks, a clamp-plate embraced snugly by said packing-ring and provided with a discharge-tube, a tubular filtration-cylinder in said casement, a washer or packing-ring provided with a central opening, clamped by said filtration-cylinder against the bottom of said clamp- 120

plate, said washer-opening affording communication between the channel of the filtration-cylinder and said discharge-pipe, a packing-disk clamped up against the bottom of the filtration-cylinder, and a latch-bar pivotally mounted upon the discharge-pipe of the clamp-plate and engaged at its ends by the hooks of the clamp-ring, substantially as described.

5. A filter, comprising a casement having an opening in its bottom, a flexible packing-ring clamped in its upper end, a clamp-plate embraced externally and snugly by the packing-ring and provided with a central passage, a discharge-pipe communicating therewith, a boss depending centrally and provided with radial passages communicating with said central passages, a tie-rod connected to and de-

pending from said boss, a washer at the bottom of the clamp-plate and provided with an opening through which said boss depends, a tubular filtration-stone surrounding said tie-rod and having its channel in communication with the opening of said washer and with the radial passages of said boss, a packing-disk at the bottom of said stone, and a nut clamping said disk against the bottom of said stone, and said stone against the washer at the bottom of the clamping-plate, substantially as and for the purpose described.

In testimony whereof I affix my signature in the presence of two witnesses.
